(57) **CLAIM**

I claim the ornamental design for a base for a temporary barrier panel, as shown and described.

DESCRIPTION

FIG. 1 is a perspective view of a base for a temporary barrier panel, showing the front, the top, and the first side of the base; FIG. 2 is a perspective view of the base, showing the front, the bottom, and the first side of the base;

FIG. 3 is a perspective view of the base, showing the rear, the top, and the first side of the base;

FIG. 4 is a perspective view of the base, showing the rear, the bottom, and the first side of the base;

FIG. 5 is an elevation view of the base, showing the first side of the base;

FIG. 6 is an elevation view of the base, showing the second side of the base; and,

FIG. 7 is a plan view of the base, showing the top of the base.
